(57) **CLAIM**

The ornamental design for a metal air vent deflector as shown and described.

DESCRIPTION

FIG. 1 is a front view of a metal air vent deflector, showing my new design;

FIG. 2 is a back view thereof;

FIG. 3 is a bottom view thereof;

FIG. 4 is a top perspective view thereof;

FIG. 5 is a right-side perspective view thereof;

FIG. 6 is a left-side perspective view thereof;

FIG. 7 is a right-side view; and,

FIG. 8 is a left-side view.

The broken lines shown depict portions of the metal air vent deflector that form no part of the claim.

1 Claim, 7 Drawing Sheets
